UNITED STATES PATENT OFFICE.

HAROLD DE OLANETA, OF NEW HAVEN, CONNECTICUT, ASSIGNOR TO WINCHESTER REPEATING ARMS COMPANY, OF NEW HAVEN, CONNECTICUT, A CORPORATION OF CONNECTICUT.

DRY CELL.

Application filed June 18, 1920. Serial No. 390,022.

To all whom it may concern:

Be it known that I, HAROLD DE OLANETA, a citizen of the United States, residing in New Haven, New Haven County, Connecticut, have invented certain new and useful Improvements in Dry Cells, of which the following is a full, clear, and exact description.

This invention relates to dry cells, and 10 while not limited in its application to that purpose, it is primarily intended for employment in connection with small dry cells such as used with electric flash lights.

The invention pertains more especially to 15 the closure at the upper end of the dry cell cup.

One of the primary objects of the invention is the provision of a simple, inexpensive, efficient and easily assembled end closure construction for dry cells.

Another object is to furnish improved 20 means for positioning and securing within the mouth portion of the cup a disk or plug of insulating material formed prior to its insertion into the cup.

Another purpose which I have in view is 25 the provision of a dry cell having effective means for preventing either inward or outward displacement of the end closure member, there being also suitable provision for the harmless disposal of the gas generated in the cell.

To these and other ends, the invention consists in the novel features and combinations 30 of parts to be hereinafter described and claimed.

In the accompanying drawing:

Fig. 1 is a vertical central section of a dry 35 cell embodying my improvements;

Fig. 2 is an elevation, partly in section, 40 of a cell of somewhat modified form;

Figs. 3 and 4 show other modifications;

Fig. 5 is a detail perspective view of the 45 end plug shown in Fig. 3; and

Fig. 6 is a fragmentary section on an enlarged scale, of certain parts shown in Fig. 3.

I have shown my improvements applied to 50 a small dry cell of the type commonly employed in connection with pocket flash lights.

The cell comprises a drawn zinc cup 10, forming one of the electrodes. Within the cup is a cartridge 11 of suitable depolarizing material surrounding and adhering to a car-

bon pencil 12, which serves as the other electrode. The cartridge 11 is of less height 55 than the cup and is usually enclosed in a porous wrapper or envelope 13. The body of paste 14 interposed between the side surface of the cartridge and the side wall of the cup serves as a carrier or vehicle for the 60 electrolyte. A suitable centering device 15 is preferably employed for centering the cartridge within the bottom portion of the zinc cup.

In the form shown in Fig. 1, a flat washer 65 16 of paper impregnated with paraffin is laid on top of the cartridge 11, said washer having an opening whereby it may be fitted over the upwardly projecting end of the electrode 12. Above the washer 16 the wall of the zinc 70 cup is displaced in an inward direction, for example, by means of a continuous annular crimp or groove 17 that may be readily formed by spinning. The groove is created on the outer surface of the cup and the corresponding annular shoulder or bead projects within the cup at some distance above the washer 16 in order to form a seat for the washer 18. This second washer 75 may be of the same material as the first, but in the form shown it is of special shape as described more particularly in my application Serial No. 368,324, being cupped at the center so as to provide a downwardly bulged portion 18a that abuts against the upper surface of washer 16 around the central electrode. On top of the washer 18 is a pre-formed end closure member 19, consisting of a plug or disk of suitable insulating material such, for example, as insulating fibre, 80 rubber or the like. Preferably an insulating fibre composition is used, a disk of appropriate size being cut from a sheet of the desired thickness and perforated centrally so that the central perforation will fit nicely 85 over the central electrode 12. The insulating fibre disk rests upon and is supported by the peripheral portion of the washer 18. Above the disk 19 the edge of the zinc cup is bent over laterally so as to overlie the top 90 surface of the disk 19 at the periphery thereof. Preferably the metal at the edge of the zinc cup is spun over the disk 19 as shown at 20, by means of a suitable spinning roller or the like, and preferably also the spinning 95 operation will be so carried out or the metal

otherwise bent or shaped that the edge portion of the cup is turned reversely so that the extreme edge will be directed substantially in the reverse direction and will bite or tend to bite into the upper surface of the disk 19, as shown more particularly in Fig. 6, where a similar construction is employed. The disk 19 being made of yielding material, the reversely turned edge of the zinc cup bites into or is imbedded in the same to a certain extent. The result is the provision of a very neat joint which is very tight and secure. The spinning of the edge of the zinc cup so that the same will be turned reversely in this manner may be produced by suitable profiling or grooving of a spinning roller or other tool. By this spinning or similar operation, the upper edge portion of the cup is rounded so that the upwardly facing portion thereof is formed on an easy curve or fillet, the effect being to increase the thickness of the edge of the cup as well as to round it and to eliminate all sharp edges projecting upwardly or tending to do so. The finish of the cell is very neat, the cup edge is reinforced, and the upper end portion of the cell may be handled more comfortably than heretofore, owing to the absence of sharp projecting metal at the upper periphery of the cup.

In the form shown in Fig. 1, the fibre disk and the cupped washer 18 are both tightly held in place between the annular inwardly projecting shoulder (formed by spinning the groove or the like) and the lapped over portion 20. The cupped washer 18, as will be noted, holds the cartridge within the cup in a certain position and maintains a gas space 21 in which the gases generated by electric or thermic action or both may be received and disposed of harmlessly.

On top of the carbon electrode is the usual contact cap 22. This may be placed on the electrode after the assembling of the other parts.

The form shown in Fig. 2 is the same as that illustrated in Fig. 1, with the exception that the paper washer 16 is omitted. In this instance the cupped washer 18 abuts directly against the upper surface of the cartridge 11.

In the form shown in Fig. 3, the cupped washer 18 is omitted, but the washer 16 is retained. In this case the end disk 19^a is directly confined at its lower part by the inwardly directed spun shoulder. The washer 16 may be forced inwardly past the shoulder, or the groove creating the shoulder may be formed after the introduction of the paper washer. In the case illustrated in Fig. 3, the frictional contact between the edge of the paper washer and the wall of the zinc cup is relied upon to hold the cartridge in place and to maintain the gas

space 23 between the washer and the disk 19^a.

In the form shown in Fig. 4, the construction is the same as that illustrated in Fig. 3, except that a disk 19^b is substituted for the washer 16. In this case it may be assumed that the metal intermediate the upper and lower disks is crimped at 17 after the disks have been inserted into the cup.

By my invention, a very neat, smooth joint is provided at the upper edge of the cup. It is not necessary in all cases, however, to have the edge of the cup reversely turned so as to bite into the closure disk as herein particularly described. Variation may be made in this and other respects without departing from the scope of the invention as defined in the claims.

In all of the cases illustrated, I employ an end closure member which is shaped prior to its introduction into the cup and which does not undergo any substantial deformation when the same is locked within the mouth of the cup. It is preferred to have a bend in the cup wall beneath the end closure member to prevent it from being forced inwardly, so that this function will be performed by the cup wall or, at any rate, by a part other than the cartridge, to thereby prevent crushing or deformation of the cartridge as a result of pressure exerted from the outside against the end plug or disk. It is also desirable to lap the metal at the edge of the cup over the upper surface of the disk as herein described. This disk is securely locked in place by integral securing means on the cup wall located above and below the disk, respectively, which does away with the necessity of deforming the disk when locking it in place. It is also preferred, as stated, to spin the edge of the cup so as to cause it to bite into the disk, but this is not essential in all cases.

In the form shown in Fig. 2, there is provided in combination with the end closure disk or plug, a special member which spaces the cartridge from the disk independently of the annular shoulder 17, which may be omitted so far as certain aspects of the invention are concerned; but in the form shown in Figs. 3 and 4, the shoulder 17 or its equivalent is relied upon to space the upper and lower disklike members apart and thereby maintain a chamber for the accommodation of the gas evolved in the cell.

I do not claim broadly herein a dry cell of the Leclanche type comprising a sheet metal cup, a cartridge therein of less height than the cup having an upwardly projecting carbon pencil as a part thereof, a body of paste interposed between the side surface of the cartridge and the side wall of the cup and extending approximately to the level of the upper cartridge surface, and a pre-

formed end plug of suitable insulating material snugly fitted within the mouth portion of the cup and having an opening whereby it is fitted over the carbon pencil 5 for centering the carbon pencil and cartridge in the cup as the end plug is inserted in the latter, as claimed in my application, Serial No. 321,068; nor do I claim herein the combination, in a dry cell, of a cup, a 10 preformed disk of insulating material located within the mouth portion of the cup and having an opening therein, and an electrode pencil engaging said opening for centering said pencil in the cup, said disk and 15 the other cell parts being constructed and arranged to present a gas chamber beneath and adjacent to the lower face of the disk, as claimed in my application, Serial No. 379,516; nor do I claim herein a thin end- 20 closure-supporting member in the mouth of the cup, perforated to fit about the upper end of the central electrode and having a downwardly bulged portion supported on top of the cartridge, as claimed in my ap- 25 plication Serial No. 368,324; nor do I claim broadly herein a preformed insulating disk locked in the mouth of the cup at some dis- 30 tance above the cartridge to provide a gas space, as claimed in my application Serial No. 390,019.

What I claim is:

1. A dry cell, having a sheet metal cup and a preformed end closure disk over which the edge of the cup at the mouth portion thereof is lapped.
2. A dry cell, having a sheet metal cup, a disk inserted in the end of the same and over which the edge portion of the cup is lapped, a cartridge within the cup having an electrode projecting through said disk, and means independent of the cartridge for preventing inward displacement of the disk.
3. A dry cell, having a sheet metal cup with an annular shoulder spun therein and an electrode centering end closure member supported from beneath by said shoulder.
4. A dry cell, having a sheet metal cup, the wall of which is displaced inwardly at a point near, but not at, the extreme edge portion of the cup, and a perforated electrode centering closure member supported above the inwardly displaced portion of the wall.
5. A dry cell, having a sheet metal cup, the wall of which is displaced inwardly at a point near, but not at, the extreme edge portion of the cup, a closure member supported on the inwardly displaced portion of the wall, and means for preventing outward displacement of said closure member.
6. A dry cell, having a sheet metal cup, the wall of which is displaced inwardly at a point near, but not at, the extreme edge portion of the cup, a perforated electrode centering closure member supported on the inwardly displaced portion of the wall, and

means for preventing outward displacement of said closure member, said last named means consisting of a rounded edge portion at the extreme edge of the cup mouth overlying said closure member.

7. A dry cell, having a thin zinc cup with a preformed end disk inserted within the mouth thereof, the metal at the edge of the cup being spun laterally so as to extend somewhat over the upper face of the disk.

8. A dry cell, having a metal cup and a closure member in the mouth of the cup against which the edge of the cup is re- 75 versely turned.

9. A dry cell, having a thin metal cup and a yielding preformed insulating disk in the mouth of the cup, the edge portion of the cup being turned inwardly and reversely and imbedded in said disk.

10. A dry cell, having a sheet metal cup with an annular inwardly projecting bead within the wall thereof and a closure member positioned above said bead.

11. A dry cell, having a sheet metal cup with an inwardly directed flange at the upper edge, an inwardly projecting bead below the flange, and closure means positioned between the flange and the bead.

12. A dry cell, having a sheet metal cup with an inwardly directed flange at the upper edge, an inwardly projecting bead below the flange, and closure means positioned between the flange and the bead, the flange being reversely turned at its extremity.

13. A dry cell, having a sheet metal recep- 100 tacle in the mouth of which spaced disklike members are positioned, the metal of the receptacle wall being displaced inwardly between said members.

14. In a dry cell, a cup, a cartridge there- 105 in having an upwardly projecting electrode, an end disk in the mouth of the cup for closing the same, and a separate member interposed between the end disk and the cartridge for maintaining a gas space in the upper portion of the cell.

15. In a dry cell, a cup, a cartridge therein having an upwardly projecting electrode, an end disk in the mouth of the cup for closing the same, and a separate washer interposed between the end disk and the cartridge for maintaining a gas space in the upper portion of the cell.

16. In a dry cell, a cup, a cartridge therein having an upwardly projecting electrode, an end disk in the mouth of the cup for closing the same, a separate washer interposed between the end disk and the cartridge for maintaining a gas space in the upper portion of the cell, and means for locking the end disk and washer against displacement.

17. In a dry cell, a sheet metal cup, a car- 125 tridge therein having an upwardly projecting electrode, a preformed disk inserted in the mouth of the cup at some distance above

- the top of the cartridge so as to create a gas space, and a crimped portion in the cup wall intermediate the disk and cartridge.
18. In a dry cell, a sheet metal cup, a cartridge therein having an upwardly projecting electrode, a preformed disk inserted in the mouth of the cup at some distance above the top of the cartridge so as to create a gas space, and a crimped portion in the cup wall intermediate the disk and cartridge, adapted to prevent inward displacement of the disk.
19. In a dry cell, a sheet metal cup, a cartridge therein of less height than the cup, having an upwardly projecting electrode, a preformed disk surrounding the upper portion of the electrode within the mouth of the cup substantially above the upper surface of the cartridge, a washer resting against the upper surface of the cartridge, and a body of paste yieldably confined by the washer, the wall of the cup being indented beneath the disk and above the washer and there being a gas space between the disk and washer.
20. In a dry cell, a cup, a cartridge therein having an upwardly projecting pencil, a body of paste surrounding the cartridge and extending approximately to the upper end thereof, a yielding washer supported on top of the cartridge and overlying the paste, a preformed end disk in the mouth of the cup for closing the same, the wall of the cup having an inwardly projecting bead on which said disk is supported, said bead being located between the disk and the washer, and means for preventing outward displacement of the disk, said disk provided with an opening for centering the cartridge pencil.
21. A dry cell having a thin zinc cup with a preformed disk inserted within the mouth thereof, the metal at the edge of the cup being thickened.
22. A dry cell having a thin zinc cup with a preformed disk inserted within the mouth thereof, the metal at the edge of the cup being thickened and rounded.
23. A dry cell having a thin zinc cup with a preformed disk inserted within the mouth thereof, the metal at the edge of the cup being thickened and rounded, and overlying the upper face of said disk to prevent displacement thereof.
24. A dry cell having a thin zinc cup with a preformed disk inserted within the mouth thereof, the metal at the edge of the cup being thickened and rounded, and overlying the upper face of said disk to prevent displacement thereof, and the wall of said cup having an inwardly projecting bead imme- diately beneath said disk to support the same from below.
25. A dry cell having a thin zinc cup, a cartridge in the cup with an upwardly projecting pencil, a body of paste interposed between the side surface of the cartridge and the side wall of the cup and extending approximately to the level of the upper surface of the cartridge, and a preformed closure disk of insulating material inserted within the mouth portion of the cup and having a centering opening fitting over said pencil, the metal at the upper part of the cup being displaced so as to extend over the peripheral upper and lower surfaces of the disk and thereby prevent displacement of said disk.
26. A dry cell having a thin zinc cup, a cartridge in the cup with an upwardly projecting pencil, a body of paste interposed between the side surface of the cartridge and the side wall of the cup and extending approximately to the level of the upper surface of the cartridge, and a preformed closure disk of insulating material inserted within the mouth portion of the cup, and having a centering opening fitting over said pencil, the metal at the upper part of the cup being displaced so as to extend over the peripheral upper and lower surfaces of the disk and thereby prevent displacement of said disk, the lower surface of the disk being spaced upwardly from the top of the cartridge body to provide a gas space.
27. A dry cell having a sheet metal cup with upper and lower spaced disklike members positioned within the mouth portion thereof, the metal of the cup wall being displaced inwardly between said members to preserve the spacing thereof, a cartridge in the cup having a pencil projecting upwardly through said members, and a body of paste interposed between the cartridge and the side wall of the cup.
28. A dry cell having a thin metal cup and a preformed insulating disk in the mouth of the cup for centering an outwardly projecting electrode, the edge portion of the cup being thickened and rounded and reversely turned.
29. A zinc cup for a dry cell having a thickened and rounded inturned edge.
30. A dry cell having a thin zinc cup with closure means within the mouth thereof, the metal at the edge of the cup being thickened and rounded and overlying the closure means.
- In witness whereof I have hereunto set my hand on the 16th day of June, 1920.

HAROLD DE OLANETA.
